Justin G. Sanders

(57) **CLAIM**

The ornamental design for a cycle backrest, as shown and described.

DESCRIPTION

FIG. 1 is a top, front and right-side perspective cycle backrest embodying my new design in accordance to a first embodiment;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and

FIG. 7 is a bottom plan view thereof.

FIG. 8 is a top, front and right-side perspective cycle backrest embodying my new design in accordance to a second embodiment;

FIG. 9 is a front elevation view thereof;

FIG. 10 is a rear elevation view thereof;

FIG. 11 is a right-side elevation view thereof;

FIG. 12 is a left-side elevation view thereof;

FIG. 13 is a top plan view thereof; and,

FIG. 14 is a bottom plan view thereof.

The broken lines in the drawings illustrate portions of the cycle backrest that form no part of the claimed design.

1 Claim, 12 Drawing Sheets
